ROTARY CRIMPER FOR CIGAR MACHINES

Lester Ferenci, Brooklyn, N. Y., assignor to International Cigar Machinery Co., a corporation of New Jersey

Application December 23, 1940, Serial No. 371,320

33 Claims. (Cl. 131—91)

This invention relates to improvements in cigar machines and more particularly to cigar bunch shapers and to the means for carrying cigar bunches to and from cigar bunch shapers.

Cigar crimpers used heretofore have been of the intermittently operated type; that is to say, they always had to stop operating while a cigar bunch was being inserted or taken out of the jaws of the crimper. Of course this necessarily slowed the machine down and did not provide for a smooth continuous operation of the crimping mechanism.

It is therefore an object of the present invention to provide a simplified and improved cigar crimper which has a rapid and continuous operation and which does not have to be stopped while a cigar bunch is being inserted between or taken out from the jaws of the crimper.

It is also an object of the invention to utilize this principle of continuous operation, which will be hereinafter disclosed, for both single and multiplex crimping devices.

A further object is to provide an improved cigar bunch transfer device which will satisfactorily transfer cigar bunches to and from a continuously revolving bunch shaping mechanism.

A further object is to provide continuously rotating bunch shapers in which there will be such relative motion of the shaping members at the time of their separation as to sufficiently loosen the bunch in a peeling manner from the faces of the bunch shaping members to prevent possible injury to the bunch.

It is also an object to provide a simplified means for obtaining any type relative motion between cigar shaping members as may be desired when opening or closing the shaping members.

Another object is to provide an improved and simplified crimper which will crimp a cigar bunch by purely arcuate movement of the crimping members and which will be a self-contained unit having only one connection to a moving part of the cigar machine.

A further object is to provide crimping jaws which will be of improved and simplified construction and which can be quickly and easily adjusted to align the same with respect to one another and also to handle different length cigar bunches.

It is also an object to provide adjustable crimper jaws each of which can be set independently of any other jaw of the crimper.

It is also an object to provide a simplified and improved multiplex cigar bunch crimper which

can be used with a high speed cigar machine and thereby allow the time for crimping a cigar bunch to be increased without diminishing the speed of the cigar machine.

Other objects and features of the invention will appear as the description of the particular physical embodiment selected to illustrate the invention progresses.

In the accompanying drawings, which form a part of this specification, like characters of reference have been applied to corresponding parts throughout the several views which make up the drawings, in which:

Fig. 1 is a side elevation, partly in section, of the crimper;

Fig. 2 is a sectional elevation on line 2—2 of Fig. 1 and also showing a sectional elevation of the means for transferring the bunch from the softening drum to the crimper as well as a softening drum, a locating means and a cigar bunch removing transfer;

Fig. 3 is a plan view of the crimper as indicated by line 3—3 of Fig. 1, the bunch trimming devices being omitted;

Fig. 4 is a sectional elevation of the crimper illustrating the position of the crimper arms in the different stages of operation and also showing a portion of the bunch inserting and removing mechanisms;

Fig. 5 is a sectional view taken on the line 5—5 of Fig. 1;

Fig. 6 is a sectional view taken on the line 6—6 of Fig. 1; and

Fig. 7 is a sectional view taken on the line 7—7 of Fig. 1.

Referring to the drawings, in Fig. 1 the main drive of the cigar machine is connected to coupling 10 of shaft 12, this connection, as will appear, being the only drive connection necessary for the operation of the shaper. Pinion 14 attached to shaft 12 meshes with gear 16 to which is secured a gear 18. Both gears 16 and 18 rotate freely on stationary stud 20. Gear 18 meshes with gear 22 which is secured to shaft 24 which is free to rotate in bearings 26 and 28 in stationary cam brackets 30 and 32 respectively, these brackets having cam tracks or grooves for controlling the operation of the shaping members as will be hereinafter described.

It is therefore possible in the present invention to obtain any type opening, closing or peeling motion of the crimper jaws as might be desired, by merely substituting a cam track having contours which will produce the desired relative motions between the opposed crimper jaws as

mentioned above. Desirable opening and closing motions of the crimper jaws, such as shown in U. S. Patent No. 1,729,440, may therefore be easily obtained.

The cam bracket 32 is secured at its lower portion by clamp screws 61 passing through lugs 59 formed thereon and threaded into table 32a (Fig. 3) to hold the bracket in place. Cam bracket 30 is supported by table 38a (Fig. 3). The cam brackets may be removed and replaced with other cam brackets having cam tracks of different contour.

A barrel-shaped frame 34, which is secured to shaft 24, has a cup shaped flange at each of its ends which provide bearings for shafts 36, 38, 40 and 42, to each of which are attached crimper arms 33, 44—35, 46—37, 48—and 39, 50 respectively, on which are formed the crimper jaws for the tuck and the head ends of the cigars.

It will be noted that the opposed bunch shaping jaws have convex and concave facings 45 and 47 which enable the jaws to close at substantially right angles to one another. Although these jaws are shown to be integral with the crimper arms 44, 46, 48 and 50, and 33, 35, 37 and 39, they may also be removably attached thereto in order to allow them to be quickly replaced.

Each of the shafts 36, 38, 40 and 42 is provided at one end with a lever having a cam roller which engages in a cam groove in one or the other of the cam brackets 30 and 32. The cam rollers 43 and 52 of the levers 41 and 54, which are attached to the adjacent ends of the shafts 36 and 40, engage in a cam groove 57 formed in the cam bracket 30, these shafts supporting the crimper arms 33, 44 and 37, 48 of the two shaping devices. The cam rollers 56 and 60 of the levers 58 and 62, which are attached to the adjoining ends of the shafts 38 and 42, engage in a cam groove 55 formed in the other cam bracket 32, these shafts supporting the crimper arms 35, 46 and 39, 50 of the shaping devices. The cam grooves 55 and 57 are so formed as to effect turning movements of the various shafts at the proper time to effect the required opening and closing movements of the shaping jaws.

It will be remembered that to enable a shaped bunch to be removed from a shaping device and a new bunch to be delivered thereto, the arms 33 and 44 are moved backwardly with respect to the direction of rotation of the supporting member 34 and the arms 35 and 46 are moved outwardly, as indicated by the dotted arrows in Fig. 4 at the dotted positions of the crimper arms shown adjacent the bunch position B6a, to permit removal of the bunch from position B6a by the transfer fingers 88 and 90. After receiving a bunch upon their jaws, the arms 35 and 46 are moved inwardly and the arms 33 and 44 are moved forwardly with respect to the said direction of rotation to grip the bunch ends between the shaping surfaces 45 and 47, as indicated by the solid arrows at the full line positions of arms 44 and 46 shown in Fig. 4, until they reach the fully closed position shown in Figs. 2 and 4. This position of the crimper arms corresponds to the dotted positions of the arms shown for bunch position B2a in Fig. 4, but the arms are fully closed before they reach position B3a. The shaping surfaces of the jaws of each opposed or cooperating pair of arms (as the arms 48 and 50) are properly shaped, as shown in dotted lines in Fig. 1, to produce the desired conical or tapered end

formation of the cigar bunch when the jaws are closed.

Cam track 55 of cam bracket 32 (Fig. 5) is designed to actuate cam levers 58 and 62 which in turn causes the swinging movements of crimper arms 35, 46 and 39, 50 respectively, thereby effecting an opening and closing of the crimper jaws of said crimper arms. The portion 210 of track 55, causes said crimper arms to open, allowing a finished shaped cigar bunch to be extracted from their crimper jaws, at the bunch position B6a (Fig. 4), by means of transfer fingers 88 and 90, as the frame 34 is rotated in the direction of the arrow (Fig. 5). Said jaws then remain open until a new bunch is inserted by fingers 88 and 90, after which a gradual closing of said jaws will be effected by portion 212 of cam 55. As the respective rollers 56 and 60 of arms 58 and 62 reach the concentric portion 214, the jaws are closed and remain closed while said rollers pass through said concentric portion. The rollers follow the cam track in the direction indicated by an arrow in Fig. 5.

Cam track 57 of cam bracket 30 (Fig. 6) is designed to actuate cam arms 41 and 54 which in turn cause the swinging movements of their respective crimper arms 33, 44 and 37, 48. Portion 200 of track 57 causes said crimper arms to open and swing out of the way while a finished shaped bunch is lifted out of the crimper jaws by transfer fingers 88 and 90 at bunch position B6a. Portion 202 keeps said crimper arms in an open position and portion 204 effects a closing of the same after a new bunch has been inserted into the crimper jaws by means of fingers 68 and 70. The concentric portion 206 keeps jaws 45 on arms 33, 44 and 37, 48 in a closed position during which time the bunch is shaped. Rollers 43 and 52 of arms 41 and 54 respectively, follow the cam track 30 in the direction of the arrow indicated in Fig. 6.

Cam track 22a in gear 22 (Fig. 7) guides the cam roller 114 which through cam lever 112 and arm 108 effects the swinging movement of transfer fingers 88 and 90 while the latter lift the finished shaped cigar bunch out of crimper jaws 45 and 47. Since two sets of crimper jaws are disclosed in this application, said transfer fingers are doing two lifting operations during one cycle of the machine. Therefore two high portions 220 of the same size and shape located exactly opposite each other are provided in the otherwise concentric cam track 22a.

Referring to Fig. 2, the bunch is shown at B1 having been delivered from the rolling table and deposited in the cradle 64 of the bunch softener 66 in a manner similar to the operation described in pending patent application, Ser. No. 234,001, filed October 8, 1938 by H. H. Wheeler.

As the bunch B1 proceeds through the softener, it is intercepted at B2 by gripper fingers 68 and 70, and is held securely therein by means of a spring 76 pulling said fingers together. Gripper finger 68 is secured to shaft 72, and finger 70 is free to swing on this shaft to a limited extent. A set screw 74 limits the closed position of finger 70 as it is acted on by closing spring 76. The transfer fingers 88 and 90 of the bunch transfer shown in Fig. 2 may be similarly connected by a tension spring 88a which acts to pull them together, and the closed position thereof may be similarly limited by a stop screw 90a threaded into one of these fingers and engaging the other finger.

When the bunch has been gripped by fingers 68 and 70, as shown in position B2, an arm 78,

having the shaft 72 freely mounted in its upper end, starts swinging in the direction of the rotating crimpler. An arm 80 is fixedly attached to shaft 72 and is provided with a roller 82 which travels in a cam track 84 for controlling the angular displacement of the gripper fingers.

During the transit of the bunch from position B2 to B2a (Fig. 4), the swinging motion of arm 78 is temporarily halted at the bunch locator 86 to position the bunch axially before entering the crimpler. This operation of positioning the cigar bunch is performed in a manner similar to that described in the patent application above referred to.

As the transfer proceeds towards the crimplers, the gripping fingers, at the end of the swing of arm 78, deposit the bunch at B2a (Fig. 4) in the facings 47 of the crimpler jaws on the arms 46 and 35. The position B2a shows the bunch just before it is stripped out of fingers 88 and 90 by means of the crimpler jaws. The arms 33 and 44 having been in open position to permit entry of the bunch will then close, removing the bunch from the gripper fingers, as shown at position B3, (Fig. 2) and arms 33, 44 will then swing further and remain in this position while traveling through the positions B3a, B3b and B4 (Figs. 2 and 4). The jaws at said position are in closed gripping relationship. The frame 34 is continuously driven and does not stop for the purpose of receiving or discharging cigar bunches.

As the facings 45 and 47 on the arms 48 and 50 and 37 and 39, holding the bunch in a tight squeeze, advance in the direction of the arrow, the bunch B4 reaches the position indicated by B5, Fig. 2, where a set of gripper fingers 88 and 90 are in position to engage and pick up the advancing bunch for transfer to the wrapping mechanism (not shown).

Since the crimpling device continuously rotates, a novel and improved cigar bunch transfer mechanism has been provided which moves a short distance in the direction of the crimpler's rotation in order to remove the cigar bunch without injuring the same. The present device is an improvement over the transfer shown in U. S. Patent No. 1,786,608. Therefore, in order to maneuver the gripper fingers 88 and 90 into position to properly engage and follow the bunch as it travels in its circular path, the shaft 92, from which the fingers 88 and 90 are suspended, is connected by means of a sprocket 94 and an endless chain 96 to a sprocket 98. The shaft 102 is supported by suitable bearing brackets 130. The arm 126 is fixedly secured to sleeve 128 which is freely mounted on shaft 102. The sleeve 128 is connected to suitable operating mechanism, such as the pinion 24 and rack 23 shown in Patent 1,786,608, so as to impart timed oscillating movement to the transfer arm 126 to carry the fingers 88 and 90 from a predetermined bunch depositing position to the dotted position of these fingers (Fig. 2) wherein they encompass the bunch at position B6, the fingers spreading apart against the resistance of spring 88a as they engage the bunch during the descent of arm 126 and thereby gripping the bunch. Lever 100, operated by means of link 104, imparts actuating movement to shaft 102. This movement of shaft 102 in turn, through sprockets 98 and 94 and chain 96, causes swinging movement to be imparted to the transfer fingers 88 and 90 from their full line position adjacent bunch position B5 in Fig. 2 to the dotted position wherein they have carried the bunch to the position B7, so that

they can follow the crimpling jaws for a short distance when removing a cigar bunch therefrom. The movement of the arm 126 may be momentarily interrupted while the transfer fingers grip the bunch at position B6 and swing along therewith in the direction of rotation of the crimpler jaws. The end of lever 100 is connected by a link 104 to a sliding toothed rack bar 106 which meshes with a gear segment 108. Suitable studs such as 101 and 103 connect the lever and rack bar to the link 104. This segment is pivoted at 110 and an arm 112 has a roller 114 which operates in a cam groove 22a formed in gear 22 (Figs. 1 and 2). The gear segment 108, operated by means of 15 the cam roller 114 following the cam groove 22a formed in gear 22, coacts with the toothed rack bar 106 to swing the lever arm 100. The lever arm 100 in turn, by means of the sprocket chain 96, swings the gripper fingers a short distance in the direction of rotation of the crimpling mechanism when lifting the crimped cigar bunch from the crimpler jaws. When the cigar bunch has been removed from the crimpling device, the gripper fingers are returned to their substantially vertical 20 position by means of the further action of the cam groove mentioned above upon the cam roller 114 and maintained in said vertical position, while the arm 126 moves toward and back from bunch depositing position, by the turning of 25 sprocket 94 created by holding the sprocket 98 stationary at this time.

When the bunch reaches the position indicated by B6, the gripper fingers 88 and 90 have encompassed and gripped the bunch and hold it while 35 following its advance in the crimplers.

The position B6a (Fig. 4) shows how the crimpler jaws separate along angular paths of travel in order to effect a peeling motion and thereby loosen the bunch from the jaws before 40 separating. The transfer fingers continue their travel to position B7 (Fig. 2) and thence to a bunch depositing station.

While in transit the bunch, as it is held squeezed in the crimplers, passes by two stationary knives 116 and 118 which trim off any tobacco that may protrude from between the concave facings 45 and 47 at either the head or the tuck end of the bunch. In order that the knives might slide against the end of said facings without damaging either the knives or the facings, beveled run-up portions 49 51a and 51 are formed at the ends of the crimpler jaws 46, 35 and 50, 39 for the knives to slide up on. The knives themselves are also slantingly formed in order to be 55 more efficient in cutting the overhanging tobacco ends.

The crimpler arms 44, 46, 48 and 50 are adjustably mounted on their respective shafts 36, 38, 40 and 42, by suitable means such as clamp screws 53, in order to accommodate cigar bunches of 60 different length, and the knives 116 and 118 are similarly mounted on a bar 120 by suitable means such as clamp screws 121.

It will be noted that the manner in which the 65 crimpler arms are mounted enables the jaws to be adjusted not only axially as stated above for accommodating different length cigars, but they may also be adjusted radially for the purpose of aligning the opposing jaws with one another. As a result, it is no longer necessary that there be such great accuracy in forming the component parts of the crimpler jaws since they can now be more readily aligned after being mounted upon their respective shafts.

Although the crimpling device has been shown

in the form of a duplex crimper having two sets of jaws, it is also possible to embody the disclosures of this application in a crimping device having only one pair of crimping jaws, or in a crimping device having three or more pairs of crimping jaws. In other words, applicant does not wish to limit himself to duplex crimpers only, but wishes to include within the scope of the subjoined claims crimping devices embodying the novel features of this invention regardless of the number of shaping members associated therewith, unless otherwise specifically limited therein.

The invention above described may be varied in construction within the scope of the claims, for the particular device selected to illustrate the invention is but one of many concrete embodiments of the same. The invention therefore is not to be restricted to the precise details of the structure shown and described.

What is claimed is:

1. In a cigar machine, a continuously rotating crimper comprising a rotating member, a plurality of shafts mounted in and traveling with said member, crank arms connected to one end of each of said shafts, cam followers connected to said crank arms, stationary cam tracks arranged to receive said cam followers for oscillating said shafts, spaced opposed arms fixedly connected at one end to said shafts, cigar shaping jaws connected to the other end of said arms, and means for rotating said central member so as to bring said jaws into and out of bunch shaping relation with each other.

2. In a cigar machine, a continuously rotating crimper comprising a central member rotating about a horizontal axis, a plurality of shafts parallel with said horizontal axis and movably mounted in said central member, spaced opposed arms adjustably connected to said shafts, cigar shaping jaws associated with the ends of said spaced opposed arms, and means for oscillating said shafts in timed relation so as to bring said jaws into and out of bunch shaping relation with each other.

3. In a cigar machine, a rotating crimper for shaping the ends of a cigar bunch comprising a central member continuously rotating about a substantially horizontal axis, members movably connected to said central member, arms rigidly connected to said members for swinging movement toward each other, jaws associated with the ends of said arms for shaping the ends of a cigar bunch, and means for oscillating said members in timed relation with each other so as to close and open said jaws for crimping a cigar bunch.

4. In a cigar machine, a cigar bunch transfer comprising an arm, bunch grippers carried by said arm, means for maintaining said grippers in a vertical position when said arm is oscillated between a bunch receiving station and a bunch discharging station, and means for swinging said grippers away from a vertical position when receiving a cigar bunch to be transferred.

5. In a cigar machine, a rotary crimping device comprising a continuously rotating central member, crimping jaws swingingly connected to said central member, means for bringing said jaws into and out of crimping engagement, a driving means for continuously rotating said central member, a bunch carrying transfer, fingers mounted at one end of said transfer for removing cigar bunches from the continuously rotating crimper jaws, and means for swinging said fin-

gers a short distance in the path of rotation of the crimper jaws to remove the cigar bunch without tearing the wrapper.

6. In a cigar machine, a continuously rotating crimper comprising a plurality of oppositely disposed bunch shaping members, means for moving said members relatively toward each other into bunch shaping position at one part of the crimper's path of rotation, and means for relatively moving said oppositely disposed members away from each other along angularly related paths in order to loosen the bunch from the members at another part of the crimper's path of rotation.

15 7. In a cigar machine, a continuously rotating crimper comprising a plurality of oppositely disposed bunch shaping members, means for moving said members relatively toward each other into bunch shaping position, and means for relatively moving said oppositely disposed members away from each other along angularly related paths in order to loosen the bunch from the bunch shaping members.

8. In a cigar machine, a rotating cigar bunch shaper comprising a continuously revolving central member, a plurality of paired bunch shaping opposed members disposed around said revolving central member, means for causing a pair of oppositely disposed bunch shaping members to move relatively toward each other into bunch shaping position, means for withdrawing one member of the pair from closed position, and additional means for withdrawing the other member of said pair along a path at an angle to the path of movement of the first named member in order to loosen the bunch from the members.

9. In a cigar machine, a continuously revolving crimping device comprising a revolving central member, a plurality of movable arms connected to said central member for revolution therewith, means for moving said arms toward each other at one part of the path of revolving of said central member, and for moving said arms away from each other at another part of the path of revolving of said central member.

40 10. In a cigar machine, a continuously rotating multiplex bunch forming device, comprising a rotating central member, a plurality of paired arms movably connected to said central member for rotation therewith, bunch forming jaws associated with the ends of said arms for crimping only the ends of a cigar bunch, means for producing relative closing movement of a pair of jaws along paths of travel predetermined with respect to said jaws for crimping a cigar bunch and for producing a different relative opening movement of a pair of jaws along other paths of travel predetermined with respect to said jaws to effect a peeling motion in order to properly loosen the bunch from the bunch shaping jaws.

65 11. A cigar bunch shaper comprising a continuously revolving member, a plurality of paired bunch shaping jaws movably connected to spaced opposed pivots mounted in said member having one jaw with a concave facing and another jaw with a convex facing for shaping the ends of a cigar bunch, and means for bringing said movable jaws into and out of bunch shaping relationship without changing the spaced opposed distance between said pivots.

70 12. A continuously operating cigar bunch shaper comprising a continuously revolving member, a plurality of paired bunch shaping jaws movably connected to said member, and means for

bringing said movable jaws into and out of bunch shaping relationship.

13. A cigar bunch shaper comprising a continuously rotating central member, a plurality of paired movable arms connected at one end to the central member and having bunch shaping jaws fixed to the other end thereof, and means for bringing said arms and jaws into bunch shaping relationship at approximately right angles to one another.

14. In a cigar machine, a continuously revolving cigar bunch shaping device comprising a support, shaping members movably connected to said support, and means for bringing said shaping members into and out of bunch shaping relationship with each other.

15. In a cigar machine, a cigar bunch shaping device comprising a plurality of co-operating movable opposed members mounted on separate supports, jaws mounted on the ends of said opposed members, a convex facing formed on one jaw and a concave facing formed on another jaw, and means for bringing the jaws having concave and convex facings into bunch forming relation with each other by pivoting said members on said supports.

16. In a cigar machine, the combination of a continuously revolving cigar bunch shaping device comprising shaping members, means for closing and opening said shaping members, and a cigar bunch transfer for removing cigar bunches from said shaping members while said cigar bunch shaping device is continually revolving, comprising an arm, bunch grippers carried by said arm, and means for swinging said grippers in the revolving direction of the bunch shaping device so as to avoid damaging the bunch in removing it from the moving shaping members.

17. In a cigar machine, a cigar bunch transfer comprising an arm, bunch grippers carried by said arm, and means for swinging said bunch grippers while the arm remains stationary so as to grip a cigar bunch without damaging the bunch.

18. A cigar bunch shaper comprising a continuously revolving central member, a plurality of movable arms connected at one end to the central member and having bunch shaping jaws fixed to the other end thereof, means for bringing said arms and jaws into bunch shaping relation with one another, and means for adjusting laterally the distance between said jaws to accommodate different length cigars.

19. In a cigar machine, a bunch shaping device comprising a continuously revolving member, cam actuated movable bunch shaping jaws connected to said revolving member, cam mechanism for opening said jaws along one angular path of travel with respect to each other and closing said jaws along another angular path of travel with respect to each other.

20. A cigar bunch shaper comprising a continuously revolving central member having a plurality of pivotal support members, a plurality of movable arms connected at one end to each of said pivotal support members and having bunch shaping jaws fixed to the other end thereof, means for bringing said arms and jaws into bunch shaping relation with one another, and means for adjusting said bunch shaping jaws circumferentially about said pivotal support members for aligning said bunch shaping jaws with one another.

21. In a cigar machine, a multiplex crimping device for shaping the ends of a cigar bunch comprising a continuously revolving support, a plurality of paired shaping members connected to

said support, each shaping member of each of said pairs being movably mounted, and means for bringing said shaping members into and out of bunch shaping relationship.

5 22. A cigar bunch shaper comprising a support, a pair of spaced opposed pivots fixed in relationship to each other, movable opposed bunch shaping members connected at one end to each of said pivots for shaping bunches between said members exclusively, means for causing one of said bunch shaping members to move along one arcuate path and for causing the other opposed shaping member to move along another arcuate path so as to bring said members into bunch shaping relationship by only swinging the two opposed bunch shaping members toward one another.

10 23. A cigar bunch shaper comprising a support, a pair of movable opposed bunch shaping members, each of said members being connected at one end to spaced opposed movable shafts mounted in said support, said shafts being fixed in relationship to each other and mounted for rotary movement along their longitudinal axes, means for causing each of said opposed bunch shaping members to travel toward each other at arcuate paths into juxtaposition, and for causing one of said jaws to continue its travel along an arcuate path when in juxtaposition until it arrives in bunch shaping position.

15 24. A multiplex cigar bunch crimper for shaping the ends of a plurality of cigar bunches at one time comprising a support, pairs of opposed crimping jaws for shaping cigar bunches between said pairs of jaws exclusively, movable arms connected to said support for supporting said crimping jaws, means for moving said arms into and out of bunch shaping relation, and mechanism having only one connection to a moving part of a cigar machine for imparting operating motion to the entire multiplex cigar bunch crimper.

20 25. In a cigar machine, a cigar bunch shaper comprising a support, a cigar bunch shaping member having a hooked shaped jaw connected to said support, a second cigar bunch shaping member having a hooked shaped jaw which is adapted to coact with the jaw of the first named cigar bunch shaping member, and means for bringing said jaws into cigar bunch shaping relation along arcuate paths substantially transverse to one another.

25 26. A shaper for shaping the ends of a cigar bunch consisting of a pair of shaping jaws, means for swinging one shaping jaw along one arcuate path and additional means for swinging the other shaping jaw along another arcuate path substantially transverse to the path of the first named jaw so as to crimp the ends of a cigar bunch.

30 27. A cigar bunch crimper comprising a central member, a plurality of movable arms connected at one end to the central member and having bunch shaping jaws connected to the other end thereof, means for bringing said arms and jaws into bunch shaping relation with one another, and means for adjustably setting each of said arms independently of any other arm.

35 28. Bunch shaping mechanism for a cigar machine, including a rotary support, means operative to continuously rotate said support, a shaping device mounted on said support and comprising a pair of arms pivotally mounted on the support for movement about circumferentially spaced apart pivotal axes, said arms being provided at their free ends with cooperating shaping jaws, and means operative to control the posi-

tions and angular movements of said arms during the continuous rotation of the support, said means being arranged to move one arm outwardly and the other arm rearwardly at one point in each rotation of the support to open said jaws for the removal of a shaped bunch and the reception of an unshaped bunch, and to move said one arm inwardly and said other arm forwardly at another point in said rotation to close said jaws upon the unshaped bunch.

29. Cigar bunch shaping mechanism for a cigar machine including, a continuously rotating support, means operative to continuously rotate said support, cigar shaping mechanism connected to said support for travel therewith, and means for delivering and removing cigar bunches to and from said shaping mechanism during the traveling movement thereof.

30. Transfer mechanism for removing a shaped bunch from a continuously traveling shaping device comprising, a bunch gripping device, an arm supporting said device and movable to carry said gripping device toward the path of travel of a bunch in said shaping device to engage said bunch and movable to carry said gripping device away from said path to remove the bunch, said arm being swingably mounted about an axis positioned between a bunch receiving position and a bunch delivering station, and mechanism for turning the gripping device about a pivotal mounting at the free end of said arm to maintain said device in a pendant position during the swinging movement of the arm and to effect

movement of the gripping device in the direction of travel of the bunch when receiving a bunch for transfer.

31. Cigar bunch handling and shaping mechanism comprising, a continuously rotating support, means operative to continuously rotate said support, cigar shaping mechanism connected to said support for travel therewith, and cigar transfer mechanism for delivering cigar bunches to said traveling cigar shaping mechanism during the traveling movement thereof.

32. Transfer mechanism for delivering cigar bunches to a traveling shaping device comprising, a swingable arm, a bunch gripping device movably mounted at the free end thereof, and means acting on said gripping device during the delivery of a bunch to said shaping device to cause said gripping device under the control of said arm and said means to move substantially with the shaping device for a certain distance.

33. Transfer mechanism for delivering cigar bunches to a traveling shaping device comprising, a swingable arm, a bunch gripping device movably mounted at the free end thereof, and means acting on said gripping device during the delivery of a bunch to said shaping device to cause said gripping device under the control of said arm and said means to move substantially with the shaping device for a certain distance, said means comprising an arcuate cam member engaging a cam follower on an arm connected to the gripping device.
